UNITED STATES PATENT OFFICE.

ANDREW G. SAMUELSON, OF SLATER, ASSIGNOR OF ONE-HALF TO J. H. LARSON, R. P. VILAND, OLE O. LEGVOLD, CHARLES SODERLAND, O. M. JOHNSON, E. PETERSON, AND A. K. ERSLAND, ALL OF STORY COUNTY, IOWA.

END-GATE FOR WAGONS.

SPECIFICATION forming part of Letters Patent No. 440,062, dated November 4, 1890.

Application filed December 5, 1889. Serial No. 332,723. (No model.)

To all whom it may concern:

Be it known that I, ANDREW G. SAMUELSON, a citizen of the United States of America, and resident of Slater, in the county of Story 5 and State of Iowa, have invented a new and useful Improvement in End-Gates for Wagons, of which the following is a specification.

My improvement relates to that class of end-gates that are adjustably connected with the end of a wagon-box, so that they can be locked in a closed position or opened and suspended in a horizontal position to be used as a shoveling-board.

My invention consists in the combination 15 and arrangement of metal straps having hooks on their ends, jointed braces and bolts to reinforce the wings of an end-gate, with a wagon-box and end-gate, as hereinafter set forth, and pointed out in the claims.

It also consists in connecting a cross-bar 20 with the rear end of the bottom of a wagon-box in such a manner that grain cannot lodge under the end-gate and a tight joint be made and maintained when the gate is closed.

In the accompanying drawings, Figure 1 is 25 a side view of the rear portion of a wagon-box to which the gate is permanently attached and locked in a closed position. Fig. 2 shows the end-gate in position as required to be used as a shoveling-board. Fig. 3 shows the end-gate inverted and in position for use as a seat. Fig. 4 shows the end-gate in position as required to serve as a chute to direct the grain as it is discharged from the box. Fig. 30 5 is a top view of the box, showing a cross-piece attached to support the end-gate and to prevent grain from lodging under the bottom of the end-gate.

A represents a wagon-box, and B a winged 40 end-gate of common form.

C is a metal strap that has a hook projecting at right angles from its lower end. One of these straps is fixed to the outside of the rear portion of each side of the box in such a 45 manner that the end of the hook will project forward.

Jointed braces D are pivoted to the top ends of the straps C and to the top portions and

edges of the wings on the end-gate by means of bolts, as shown, or in any suitable way. 50

Metal straps or bolts F are fixed to each wing of the end-gate at its broadest point to re-enforce the wings and also to engage the jointed braces when in position to support the end-gate for use as a shoveling-board, as 55 shown in Fig. 2, and as required to serve as fulcrums to the braces, so that the jointed braces will perform the functions of rigid levers in bearing a person's weight on the shoveling-board. 60

To close and lock the end-gate, I turn it up against the end of the box and let its bottom rest on bolts or irons g, that extend horizontally rearward from the bottom of the box to support a cross-piece h, and then press the 65 overlapping portions of the jointed braces into the hooks on the ends of the straps C. The long portions of the braces that are pivoted to the top portions of the wings of the gate pass the pivots and dead-centers on the 70 sides of the box, draw the end-gate downward and forward, and lock it tight to the ends of the sides and the bottom of the box, as required to retain grain in bulk within the box. To unlock I press the doubled portions of the 75 braces out of the hooks and forward past the dead-centers, as required to release the end-gate from their clamping and binding force.

To adjust the end-gate for use as a shoveling-board, I turn the gate rearward and downward and let its bottom portion rest on the cross-piece h and the jointed braces extend in an upwardly-bowed position and in contact with the wings of the gate, as shown in Fig. 2. The cross-piece h is fixed to the cleat on 85 the under side and end of the bottom of the box by means of bolts g in such a manner that it will not be in contact with the end of the bottom, and consequently there will be an open space between the cross-bar and the 90 box that will allow grain to fall through and prevent it from lodging on the cross-piece and interfering with closing the end of the wagon by means of the gate. The screw-threaded ends of the irons g are secured to 95 the fixed bar by means of nuts in such a man-

ner that the bar *h* can be adjusted thereby relative to the thickness of the gate and to compensate for wear or shrinkage of the bottom of the end-gate, as required to make and maintain a close fit and tight joint. The gate can also be readily placed in position without detaching any part of the fastening devices, as shown in Fig. 3, to be used for a seat, and, as shown in Fig. 4, to serve as a chute, and by sinking the hind wheels of the wagon in the ground the gate can be inverted and extended downward to serve as a platform or bridge for animals to pass over and in and out of the wagon-box.

15 I claim as my invention—

1. Metal straps *C*, having hooks on their ends and fixed to the sides of a box to extend vertically, jointed braces *D*, pivoted to the top ends of said straps *C* and pivoted to the edges

and top end portions of wings fixed to the ends of an end-gate, and straps or bolts *F*, fixed across the widest parts of the lower ends of the wings of the gate, arranged and combined to operate in the manner set forth, for the purposes stated.

25

2. In a wagon end-gate support, the combination of a movable cross-bar *h* and bolts or arms *g*, fixed thereto, with a bar fixed across the under side and rear end of the bottom of a wagon-box, for maintaining an open space between the movable bar and the fixed bar and a tight joint between the end of the wagon-box and the end-gate when closed, in the manner set forth, for the purposes stated.

30

ANDREW G. SAMUELSON.
